Inventor:

W. L. Selleck.

United States Patent Office.

W. L. SELLECK, OF BEETOWN, ASSIGNOR TO D. W. PERKINS, OF MILWAUKEE, WISCONSIN.

Letters Patent No. 105,602, dated July 19, 1870.

IMPROVEMENT IN WATER-WHEELS.

The Schedule referred to in these Letters Patent and making part of the same

To all whom it may concern:

Be it known that I, W. L. SELLECK, of Beetown, in the county of Grant and State of Wisconsin, have invented a new and useful Improvement in Water-Wheels; and I do hereby declare that the following is a full and exact description of said invention, which will enable those skilled in the art to make and use the same, reference being had to the accompanying drawing forming part of this specification, in which—

Figure 1 is a perspective view of my invention; Figure 2, a sectional view; and Figure 3, view of the bucket.

Similar letters of reference in each of the figures indicate corresponding parts.

The object of my invention is to produce a water-wheel superior to others in use.

A is the top of the stationary part of the curb. B, the hollow box for the upright shaft to work in. C, the upright wheel-shaft.

D, the gate-plate with slots in it, which, when moved, will open and close the gates.

E, pins attached to the gates, and passing up through slots in the top of A, and through diagonal slots in the plate D. As the plate D is turned, these pins are thrown out or in, and thus the gates are opened or closed.

F, chutes to give the water the proper direction onto the wheel.

G, gates.

H, the lower part of the curb.

I, pins which go through the outer arms of the gates, and on which the gates swing as they are opened or closed.

K, buckets of the wheels. These, at the upper part, project out over the lower part of the curb H, so as to take the force of the water direct, and the

lower part of the buckets has a reacting curve, so as to use the water both direct and reacting.

L, the shaft to open and close the gates with.

M, pinion on shaft L.

N, cog-gear on plate D, forming a rack into which meshes pinion M.

O, screws in box B to adjust shaft C.

P, step for shaft C.

Q, a bar across the lower part of the curb H, and in which step P stands.

R, the hub of the wheel to which buckets K are attached.

S, back flange of the buckets.

Operation.

Set the wheel in a flume surrounded with water, and turn shaft L that will open the gates, and the water, being directed by the chutes F, will first strike the buckets direct, and then will pass down onto the reacting part of the bucket and propel the wheel.

Claims.

1. A water-wheel, with upper part of the buckets K projecting out over the lower part of the curb H, and the lower part of said buckets passing down in a diagonal or reacting form, so that the water shall strike its upper part direct, and then fall slanting or reacting, substantially as described.

2. Gate-plate D, pins E, chutes F, gates G, and pins I, all in combination, substantially as described.

The above specification of my invention signed by me this 19th day of June, 1868.

W. L. SELLECK.
